United States Patent Office

Des. 212,166
Patented Sept. 3, 1968

212,166

TONGS

Larry L. Hill, P.O. Box 30,
Bristol, Ill. 60512

Filed Nov. 24, 1967, Ser. No. 9,540

Term of patent 14 years

(Cl. D44—4)

FIG. 1 is a side elevational view of tongs showing my new design;

FIG. 2 is a front elevational view;

FIG. 3 is a top plan view; and

FIG. 4 is a bottom plan view.

I claim:

The ornamental design for a tongs, substantially as shown.
